CORSET GARMENT

Samuel T. Metz, Jamaica, N. Y.

Applica

33, Serial No. 671,628 (1st) (2nd) (3rd) (4th) (5th) (6th)
Cl. 2—37) (1st) (2nd) (3rd) (4th) (5th) (6th)

My invention relates to a new and improved corset garment.

One of the objects of my invention is to provide a corset garment of the girdle type.

5. Another object of my invention is to provide a corset garment having elastic panels and also having relatively non-elastic panels, the non-elastic panels preferably forming the front and the rear of the garment.
10. Another object of my invention is to provide a garment of this type in which the panels may be more stretchable in the lateral direction than in the vertical direction.

knitted by means of vertical meshes M. These vertical knitted meshes M are much less stretchable in the vertical direction than in the horizontal or lateral direction, so that the garment has a much greater stretch in the lateral direction than in the vertical direction. However, the invention generally applies to any type of elastic panel which may be stretchable in the vertical direction to any desired extent.

10. Another object of my invention is to provide a garment of this type in which the panels may be more stretchable in the lateral direction than in the vertical direction.

Another object of my invention is to provide a garment of this type in which the non-stretchable panels are made of mesh material, said panel

els being suitably reinforced by lateral ribbons of woven material. Whenever I refer to mesh material, I intend to include voile, or any light-weight knitted or woven material which requires reinforcement, in order to stand the strain to which a corset garment is subjected.

25 Other objects of my invention will be set forth in the following description and drawings which illustrate a preferred embodiment thereof; it being understood that the above general statement of the objects of my invention is intended merely to generally explain the same and not to limit it in any manner.

30. Fig. 1 is a perspective view.
Fig. 2 is a front elevation.

Fig. 3 is a detail inside view of a corner of the garment showing how a hose supporter is connected to the garment, at the junction between an elastic panel and a non-elastic panel.

Fig. 4 is a detail outside view showing how an

Fig. 5 is a detail elevation showing a portion of the elastic panel is connected to a non-elastic panel.

40 of the top of an elastic panel and of a non-
elastic panel.

Fig. 6 is a detail view showing the connection between an elastic panel and a non-elastic panel, the parts being shown separated in this figure in order to more clearly illustrate said parts.

45 Fig. 7 is a sectional view on the line 7—7 of Fig. 5.

The garment comprises front and rear panels A and said panels are substantially identical in construction. The garment also comprises side panels B and C. The side panels may be of any desired elastic construction. In the specific embodiment illustrated, the main body of each side panel comprises elastic cords 1. Each said cord 1 is made of stretchable rubber, which is covered with one or more layers of yarn. These cords

thickness. Each elastic panel B or C is located so that one of the vertical rows of stitches 6 passes through the same and the inner vertical row of said stitches 6 skips the elastic panel, and the inturned ends of the ribbons.

In order to reinforce the connection between each elastic panel B (or C) and the adjacent non-elastic panel A, reinforcing members 9 and 10 are continuously applied. Each said reinforcing strip 9 and 10 extends completely along the garment from top to bottom. Said strips 9 and 10 may be made of any suitable knitted or woven material which is preferably non-elastic. Each reinforcing strip 10 is connected to the respective panel B or C, by means of a zig-zag or cross-stitch 11. The vertical rows of stitches 6 pass through member 9.

At its top and bottom, each of the elastic panels 5.

B and C is provided with a reinforced elastic zone 12, which is made by braiding or otherwise connecting a plurality of the elastic cords 1 and connecting said cords by a covering yarn or 5 yarns.

Referring to Fig. 3, the garment has a hose supporter connected to the bottom edge thereof at each junction between an elastic panel and a non-elastic panel. The hose supporters H are 10 made of suitable elastic material and they are stitched to the non-elastic panel A by means of horizontal stitches 16. The bottom ribbon Ra is of curved or arcuate form, as shown in Fig. 2, and said bottom ribbon Ra partially overlaps the 15 adjacent ribbon R. The bottom stitches 5 of said adjacent ribbon R pass through a part of the curved top of the bottom ribbon Ra.

In order to secure this arcuate form while using an ordinary straight ribbon, said bottom 20 ribbon Ra is folded at the points F, there being two such folds in each bottom ribbon. The top stitches 5 of the bottom ribbon Ra are above the top of the hose supporter.

Referring to Fig. 3, a reinforcing strip 17 having a nap inner surface is provided and this reinforcing strip is connected to the vertical reinforcing strip 9 by means of the outer row of 25 stitches 6, and additional stitches 20 are provided for connecting the reinforcing strip 17 to the bottom of the panel A, and also to the bottom ribbon Ra.

In addition to the four hose supporters H, which are thus provided, two additional hose supporters Ha are provided at the sides of the garment, and said additional hose supporters Ha are connected to the bottom portions 3 of the panels B and C.

The vertical stitches 6 tightly connect the members 9 and 10 to the front and back non- 40 elastic panels A, so that the inturned ends of the panels A, and the inturned ends of the ribbons R, are firmly held in position.

The mesh panels A provide proper ventilation for the garment and the ribbons R take up the 45 strain upon said mesh panels so that the garment has long life.

While I prefer to use two non-elastic and 50 ventilating panels A, I may use one such panel or any desired number of said panels.

Whenever I refer to a non-elastic panel in the claims, it is to be understood that the invention is not to be limited to a panel which has no stretchability. On the contrary, the invention includes a panel A which is less elastic or stretchable than the panels B and C. Likewise, when I refer to a non-elastic panel, the invention is not to be limited to a panel which is non-elastic in all directions, because the panels A may have a certain amount of vertical stretch or elasticity 60 without departing from the invention.

Since the non-elastic panels have spaced reinforcing strips, these strips can conform to the shape of the body and grip it more securely than if the non-elastic panels were made of ordinary heavy fabric and the strips were omitted. The width of each reinforcing strip R, may be one-half (1/2) inch more or less. The width may be as great as one inch, as long as the width is not too great to prevent the spaced strips from conforming to the shape of the body.

I have shown a preferred embodiment of my invention, but it is clear that numerous changes and omissions can be made without departing from its spirit.

I claim:

1. A corset garment having a non-elastic panel made of ventilating mesh material, said non-elastic panel having spaced horizontal reinforcing strips of material connected thereto, the ends of said spaced strips being rearwardly inturned, 20 an elastic panel which is located behind said inturned ends, and a vertical reinforcing strip which is sewed to said elastic panel and to said non-elastic panel, said reinforcing strips being of greater strength than said mesh material. 25

2. A corset garment having a non-elastic panel made of ventilating mesh material, said panel having spaced reinforcing strips sewed thereto, an elastic panel which overlaps the non-elastic panel at the rear of the said non-elastic panel, 30 a vertical reinforcing strip, part of which is located behind said non-elastic panel, said vertical reinforcing strip being connected by stitches to said elastic panel and to said non-elastic panel, said vertical reinforcing strip being connected to the elastic panel by stitches which are spaced from the non-elastic panel, said reinforcing strips being of greater strength than said mesh material. 35

3. A corset garment having a non-elastic panel made of mesh material, said panel having spaced strips of reinforcing material sewed thereto, said strips being rearwardly inturned at an edge of said panel, an elastic panel having a vertical end portion thereof located behind said inwardly turned ends, a vertical reinforcing strip located behind said elastic panel and partially overlapping said non-elastic panel, a second vertical strip located behind the first mentioned vertical strip, said vertical strips and said elastic panel being connected to the non-elastic panel by stitches which pass through said inturned ends, the second vertical strip being connected to the non-elastic panel by stitches which skip the first mentioned vertical strip and the elastic panel 50 and said inturned ends, the first mentioned vertical strip being connected to the elastic panel by means of stitches which are spaced from the non-elastic panel. 55
